UNITED STATES PATENT OFFICE.

FRANK M. LEAVITT, OF BROOKLYN, NEW YORK, ASSIGNOR TO E. W. BLISS COMPANY, OF BROOKLYN, NEW YORK, A CORPORATION OF WEST VIRGINIA.

GENERATION OF POWER FROM COMPRESSED AIR.

SPECIFICATION forming part of Letters Patent No. 693,871, dated February 25, 1902.

Application filed December 12, 1898. Serial No. 699,006. (No model.)

To all whom it may concern:

Be it known that I, FRANK M. LEAVITT, a citizen of the United States, residing in the borough of Brooklyn, county of Kings, city 5 and State of New York, have invented certain new and useful Improvements in the Generation of Power from Compressed Air, of which the following is a specification.

My invention provides an improvement on 10 the means heretofore in use for storing and generating power from compressed air for the propulsion of automobile torpedoes. Heretofore it has been customary to store the air under a high degree of compression in a reservoir, whence on the launching of the torpedo the compressed air was led to the engine and there expanded to drive the engine and propel the torpedo. According to my invention I increase the power which could 15 be developed from a given quantity of air at a given pressure under the former system and also overcome the fall of temperature, which formerly occurred upon expansion of the compressed air. These results I obtain 20 by heating the air, preferably by the combustion of a liquid hydrocarbon in the compressed-air reservoir, before conducting it to the engine.

In the practice of my invention I prefer- 25 ably store a suitable quantity of combustible material, such as alcohol or some similar liquid hydrocarbon, in a chamber communicat- 30 ing with the reservoir, and I compress air in the reservoir and retain such compressed air 35 therein for as long a time as is desired—that is, until the torpedo is to be used. In the use of the torpedo and substantially simultaneously with the opening of the valve which admits compressed air to the motor I ef- 40 feet the ignition of the combustible mate- 45 rial within the reservoir or within a chamber communicating therewith and cause the combustible material to burn therein in such manner that the air compressed in the reser- 50 voir serves to supply the oxygen for main- taining such combustion, and in such man- 55 ner also that the combustion itself effects an increase of pressure in the reservoir both by heating and expanding the air confined there- 60 in and also by adding to such air the gaseous

products resulting from the combustion. By this means not only is the pressure greatly increased at the time of utilization of the power, but the air which is undergoing an expansion in the motor instead of undergo- 65 ing a serious fall of temperature, as heretofore, so that all the working parts are rendered extremely cold, is so heated that the fall of temperature accompanying its expansion leaves it still hot or at least warm enough to 70 avoid such objectionable chilling of the parts. I effect the combustion of such material in a gradual and progressive manner, by preference commencing the combustion preferably coincidently with the fall in pressure due to 75 the first admission of air to the motor and continuing the combustion at a rate proportionate to the fall of pressure, so that any sudden or extreme increase of pressure of the already highly-compressed air in the flask 80 or reservoir at the commencement of the operation is avoided, and the rapid or excessive fall of pressure which ordinarily occurs in utilizing compressed air as a source of power is also avoided, since the added pres- 85 sure due to the combustion is progressively applied to in great part neutralize the falling pressure of the compressed air.

Having thus indicated the nature of my in- 90 vention, I will now proceed to explain the pre- 95 ferred mode of applying the same with refer- ence to the accompanying drawings, where- in—

Figure 1 is an elevation, on a small scale, showing the exterior of the apparatus. Fig. 85 2 is a vertical longitudinal mid-section of the compressed-air flask or reservoir and its ap- 90 purtenances on a larger scale. Fig. 3 is an enlarged fragmentary section showing in de- 95 tail the igniting means.

The torpedo used being of any well-known compressed-air-driven type, such as the Whitehead automobile torpedo, is not illus- 95 trated, except as to the parts which are re- quisite in illustrating the operation of my in- vention.

In Fig. 1, A is the compressed-air reservoir or flask. B is the engine or motor to be driven therefrom and which drives the propeller of the torpedo. C is the chamber for containing 100

the combustible material, and *a* is the pipe conveying compressed air from the reservoir to the motor.

Fig. 2 shows the interior of the reservoir 5 A. In this the preferred construction an inner receptacle or vessel *D* is placed therein, having an open top, but being partly covered over or inclosed by a hood *E*. A pipe *b* connects the bottom of the receptacle *C* with the 10 bottom of the chamber *D*, passing through the wall of the reservoir at some suitable point. The chamber *C* has a removable cap or filling-plug *c* at top. A tube *d* communicates from the receptacle *D* through the end of the flask 15 *A*, and its outer end is fitted with a cap *e*, through which an electric wire may be led. The pipe *a*, by which the compressed air is conducted out of the reservoir *A* to the motor *B*, leads from the interior of the hood *E*, as 20 shown. This pipe is provided with the usual throttle-valve *a'*. An electric igniting-fuse *F* (shown detached in Fig. 3) is introduced through the tube *d* by removing its cap *e*, the fuse *F* being pushed down through the 25 tube into the receptacle *D*, as shown in Fig. 2. As a means of effecting electric connection through the cap *e* and at the same time 30 withstanding the heavy pressure within the reservoir I may adopt the construction shown in Fig. 3, wherein the cap *e* is a plug having a conical portion ground to a seat with the end of the tube *d* and pressed tightly against such seat by a screw-coupling *f*. A metal pin *g*, preferably conical, passes through a 35 hole in the cap or plug *e*, being surrounded by a conical insulating-sleeve *h*, the cone being so arranged that the internal pressure tends to tighten it. Two insulated electric wires *i* and *j* are soldered, respectively, to the 40 inner end of said pin and to the metal plug *e* or other metal surface, and these wires extend thence in through the tube *d*, their opposite ends being joined by an incandescent bridge or loop *k* of fine platinum wire. The 45 fuse *F* may be variously constructed according to any known means for constructing electric fuses for blasting; but I prefer the incandescent loop *k*, and I prefer to embed this loop in loose gunpowder or in fulminate or other 50 easily-ignitable material at *l*, and preferably I lead the wires through fine holes in a block *m* of gunpowder, preferably molded smokeless powder. I prefer also to arrange adjacent to this another block or mass *n* of highly-combustible material—as, for example, soluble cotton formed into a cake with paraffin. Exterior 55 to the reservoir the electric circuit is completed by means of a wire *i'*, joined to the opposite end of the pin *g*, interrupted by any suitable sort of circuit-closer or switch *p* and leading to one pole of a battery or other electric generator *G*, from the other pole of which a wire *q* may lead to any metal part of the apparatus by which communication 60 may be established with the other wire *j*, already referred to. The circuit thus made is 65 complete except at the circuit-breaker *p*.

The mechanical construction being now understood, I will proceed to describe the preferred mode of operation.

Assuming the flask *A* to be open or air within it to be at atmospheric pressure, the cap *c* of the chamber *C* is removed, and a measured quantity of alcohol (or other suitable liquid hydrocarbon) is poured into this 70 chamber so as to fill it preferably to the level shown in Fig. 2, so that no portion of the alcohol will run out through the tube *b* into the receptacle *D*. The tube *b*, as shown in Fig. 2, is carried up to a height equal to the level 75 *x* of the liquid, whatever be the height of location of the chamber *C*. The chamber *C* should be proportioned to leave a suitable air-space above this level. After introducing this liquid the cap *c* is tightly closed. The 80 fuse *F* is then or may previously have been introduced through the tube *d* and its cap or plug *e* tightly screwed down by the union *f*. Air is then pumped in either through the pipe *a* or through a separate admission-cock 85 until the desired pressure is obtained—as, for example, fifteen hundred pounds per square inch—whereupon the admission-cock is closed, and the air thus introduced is left 90 stored in the reservoir until the torpedo is 95 launched. During this introduction of air as fast as its pressure exceeds that in the chamber *C* it will flow through the tube *b* and bubble up through the hydrocarbon in said chamber, so that the air in the upper part of 100 this chamber is compressed to the same pressure as that in the reservoir *A*. When it is desired to generate the power thus stored, the throttle-valve *a'* is opened to admit the compressed air to flow to the motor *B*, and either 105 just before or at any suitable time subsequent to this the circuit-closer *p* may be actuated, (by any suitable means,) whereby the circuit from the battery *G* is closed through the fuse *F*, thereby sending a current of sufficient 110 energy to incandesce the loop *k* and ignite the powder or fulminate *l*, this in turn igniting the gunpowder *m* and the combustible plug *n*. As soon as the air begins to escape from 115 the reservoir *A* its diminution of pressure below that of the air compressed in the chamber *C* results in an expansion of the latter, and the consequent forcing over of a portion 120 of the alcohol through the tube *b* in the chamber *D*. The operations are so timed that the ignition of the fuse *F* will not occur or at least the combustion resulting therefrom will not cease until after this flow of alcohol into 125 the receptacle *D* has commenced, so that the alcohol thus entering this chamber will be 130 ignited as it enters and will burn, its combustion being supported by the oxygen of the compressed air, so that it burns rapidly and fiercely, and its heat being given up to the compressed air the latter is increased in temperature and in pressure. The hot gases and flames resulting from this combustion mingle with the stream of air which is flowing out from the tube *a*, the direction of the

flow being indicated by the arrows in Fig. 2. Thus the heat of the combustion is concentrated within the receptacle D and hood E and within the tube a. The annular space between the receptacle D and hood E is made amply wide to permit a flow of air so slow as to avoid blowing out the flame of the burning alcohol. The alcohol enters the receptacle D gradually and progressively in proportion to the diminution of pressure in the reservoir, since it is only in this proportion that the expansion of the air confined in the chamber C is able to take place, and it is due solely to this expansion that the alcohol is expelled from this chamber and fed into the combustion chamber or receptacle D. By suitably proportioning the volume of the air-space in the chamber C to that of the reservoir A and to the quantity of alcohol the flow of the latter into the reservoir may be graduated in any manner desired. I prefer to so proportion the parts that the flow of alcohol shall be continuous during nearly the entire period of generation of power—that is, during the entire run of the torpedo—so that the last of the alcohol will not be consumed until shortly before the pressure falls to a minimum, at which it is no longer practically available for power purposes. By this means not only is the fall of pressure of the compressed air less rapid, but there is a great increase of pressure due to the heat which is liberated within the mass of compressed air, and subsequently the pressure falls much more slowly than would otherwise result, and the generation of power at a given rate can be continued for a much longer time or at a greatly increased rate for the same time. In the practical application of my invention in connection with an automobile torpedo I have in proportion to the amount of air compressed to a given pressure increased the generated horse-power by fifty per cent. as compared with the ordinary use of compressed air alone or unheated. At the same time my invention avoids the disadvantage of the cooling of the engine and passages due to the expansion of the compressed air.

My invention may be applied with any suitable combustible material—as, for example, any liquid hydrocarbon or any combustible gas—which may be compressed to the extent to which the air has to be compressed, or even a solid combustible may be used. I prefer, however, the use of a liquid combustible, as it is most easily managed and controlled, and I prefer to control its rate of combustion by introducing it progressively into the compressed-air reservoir or preferably into an open combustion-chamber located therein, as described.

My invention may be greatly modified in its practical application, and I do not limit myself to any one means of applying my invention. The means herein described is considered preferable from a practical point of view to any other which I have tried or devised

for applying the principle of my invention; but I am not to be understood as limiting myself thereto.

I claim as my invention the following-defined novel features, substantially as hereinbefore specified, namely:

1. In compressed-air propelling mechanism for automobile torpedoes, the described means for increasing the energy of the stored compressed air which consists in means controlled by the pressure for heating the compressed air.

2. In compressed-air propelling mechanism for automobile torpedoes, the described means for increasing the energy of the stored compressed air which consists in the combination of means controlled by the pressure in said reservoir for feeding a combustible thereinto and means for igniting said combustible in said reservoir.

3. In compressed-air propelling mechanism for automobile torpedoes, the described means for increasing the energy of the stored compressed air which consists in the combination of means operated by a reduction of pressure in said reservoir for feeding a combustible thereinto and means for igniting said combustible in said reservoir.

4. In compressed-air propelling mechanism for automobile torpedoes, the combination of means for igniting a combustible within the stored compressed air, with means for introducing a fluid combustible gradually during the run of the engine in proportion to the consumption of the compressed air, said means adapted to suspend its introduction and thereby stop the combustion in case of the stoppage of the engine.

5. In compressed-air propelling mechanism for automobile torpedoes, the combination of means for igniting a combustible within the stored compressed air, with means for introducing a fluid combustible gradually during the run of the engine in proportion to the consumption of the compressed air, said means adapted to suspend its introduction and thereby stop the combustion upon a cessation of fall in pressure, or upon a rise in pressure, of the compressed air.

6. In compressed-air propelling mechanism for automobile torpedoes, the described means for increasing the energy of the stored compressed air which consists in the combination of a chamber for holding a combustible charge, said chamber opening into the compressed-air reservoir, means controlled by the pressure in said reservoir for supplying a combustible charge from said chamber to said reservoir, and means for igniting said combustible in said reservoir.

7. In compressed-air propelling mechanism for automobile torpedoes, the described means for increasing the energy of the stored compressed air which consists in the combination of a compressed-air reservoir, a chamber for holding a charge of combustible fluid, a pipe leading therefrom into said reservoir,

means for igniting said fluid in the reservoir, and means acting as the pressure in the reservoir falls to feed combustible fluid from said chamber into the reservoir at a rate proportional to the fall of pressure therein.

8. In compressed-air propelling mechanism for automobile torpedoes, the described means for increasing the energy of the stored compressed air which consists in the combination of a compressed-air reservoir, a chamber for holding a charge of combustible liquid, a pipe leading therefrom into said reservoir, adapted to leave an air-space in said chamber above said liquid, and means for igniting said liquid in the reservoir, whereby as the pressure in the reservoir falls the consequent expansion of the air in said air-space expels the liquid from said chamber into the reservoir at a rate proportional to the fall of pressure therein.

9. In compressed-air propelling mechanism for automobile torpedoes, the described means for increasing the energy of the stored compressed air which consists in the combination of a compressed-air reservoir adapted to receive a charge of compressed air and to be disconnected from the source thereof, and a chamber for holding a charge of combustible liquid opening into said reservoir and adapted as air is compressed into said reservoir to admit air to said chamber under equal compression in an air-space above said liquid.

10. In compressed-air propelling mechanism for automobile torpedoes, the described means for increasing the energy of the stored compressed air which consists in the combination of a compressed-air reservoir, a motor connected thereto to be driven by compressed air therefrom, means for heating the air at a point in said reservoir and means for con-

ducting air from such point alone to said motor whereby the air which is most highly heated is continually used.

11. In compressed-air propelling mechanism for automobile torpedoes, the described means for increasing the energy of the stored compressed air which consists in the combination of a compressed-air reservoir, a motor connected thereto to be driven by compressed air therefrom, means for igniting and burning a combustible at a point in said reservoir and means for conducting air and the products of combustion from such point alone to said motor whereby the air which is most highly heated is continually used.

12. In compressed-air propelling mechanism for automobile torpedoes, the combination of a heating-receptacle in free communication with the interior of the compressed-air reservoir, means for igniting a combustible therein, means for feeding a fluid combustible gradually thereinto, and a passage for conducting the heated air and products of combustion therefrom to the engine.

13. The combination of a compressed-air reservoir, a motor connected thereto, to be driven by the compressed air therefrom, means for gradually feeding a combustible fluid into said reservoir at a rate proportional to the reduction of pressure therein during the outflow of compressed air, and means for igniting said combustible within said reservoir.

In witness whereof I have hereunto signed my name in the presence of two subscribing witnesses.

FRANK M. LEAVITT.
